Affury Wilkinson

UNITED STATES PATENT OFFICE.

ASBURY WILKINSON, OF MADISON, INDIANA.

WASHING-MACHINE.

Specification of Letters Patent No. 25,542, dated September 20, 1859.

To all whom it may concern:

Be it known that I, ASBURY WILKINSON, of the city of Madison, in the county of Jefferson and State of Indiana, have invented 5 a new and useful Improvement in Washing-Machines; and I do hereby declare the following to be a full and exact description of my invention, reference being had to the accompanying drawings, which I desire 10 to constitute a part of this specification, like letters in every figure referring to like parts.

The nature of my invention consists in providing two self adjusting circular shaped wash boards between which a corrugated 15 roller is made to revolve, thus converting the reciprocating motion (found in most all machines) into rotary—continuous rotary motion. The advantages of this will appear in the following description, to which I now 20 proceed in order that others skilled in the art, may be able to make and use my invention.

In the accompanying drawings, it will be seen that Figure 1 is an upright perspective 25 view of the whole machine together, complete. Fig. 2 is the self adjusting circular shaped wash-board which is suspended by springs on the under side of the corrugated roller Fig. 4. Fig. 3 is the top wash-board, 30 under which the corrugated roller plays.

A, represents a plain square or otherwise shaped box for containing the soap suds and the clothes (the unwashed at one end, and those that have passed through the machine at the other end). Also, in this box are suspended from the rack a, a, a, the circular wash boards B and C by spiral springs b, b, &c.

Fig. 4—the corrugated roller, is provided 40 with a round shaft h, h, passing through its center, by means of which it is suspended in the center of box A. Its corrugations may be round, or sharp, on their outer surface, but must run lengthwise of the roller 45 (i, i, &c). This roller is driven by the crank J. The box, roller, and everything connected with the machine may be made to suit the fancy of the mechanic as to size,

&c. The corrugations on the periphery of roller Fig. 4 must be stationary, and the 50 corrugations (i, i, &c) in the circular wash boards B and C must be made round and turn upon bearings at their ends.

The pin f on frame a, a, catches on the underside of key a', a', and serves to hold 55 not only said frame in place, but also the shaft h, h, of the roller Fig. 4. Crank J serves to rotate this roller.

What I consider new in my machine is, the combination and peculiar arrangement 60 of circular boards B and C, suspended by springs, with the roller Fig. 4 playing between them. The advantages of this arrangement are self evident, viz: 1st. It makes a machine as perfectly anti-friction as possible. 2nd. The board C, suspended above, not only facilitates the washing process, but causes the clothes to keep a continuous over and over motion, as it catches them as soon as they emerge from beneath the corrugated 70 roller and passes them over to the other side and a rubbing process, and 3d, these boards B and C being suspended by springs (spiral are the best, though other forms of springs may be used) gives to them a self-adjusting 75 quality not found on any machine of similar construction. By this too the pressure may be graduated to suit the kind of work the machine is required to perform.

I do not wish to be understood as claiming, broadly, the construction of a washing machine composed of board B, and corrugated roller Fig. 4, as I am aware that similar devices have long been known, but,

What I do claim as new, and desire to 85 secure Letters Patent upon, is,

The combination of circular boards B and C, suspended from a frame above, by springs b, b, b, &c, with a rotary corrugated roller Fig. 4, working between them; all 90 constructed and operated substantially as set forth in the foregoing specification.

ASBURY WILKINSON.
